UNITED STATES PATENT OFFICE.

CHRISTIAN A. CHRISTOFFERSON, OF ST. PAUL, MINNESOTA.

AUTOMATIC STORM-WINDOW REGULATOR.

Application filed February 8, 1926. Serial No. 86,850.

This invention relates to an attachment for windows, adapted to automatically effect the opening or closing of a pivoted storm sash upon the opening or closing of a sliding sash of common type.

In localities where cold weather prevails for a large part of the year, it is common to secure additional protection from the elements by applying storm sash to the windows of dwellings. Such storm sash are usually pivoted upon the window frames at their upper ends, so as to permit opening at night or at other times when fresh air is desired in a room. The fastening devices heretofore provided for holding such storm sash in predetermined open or closed position have not been entirely satisfactory, because when they hold the sash securely, they are apt to jam or are otherwise difficult to manipulate. This is especially true when, as frequently occurs, such fastening devices become rusted or corroded. To manipulate a storm sash from within doors, the inner, sliding sash must be open, and heretofore it has been necessary for one closing windows of this kind to expose himself to the elements while he manipulates the storm sash fastenings.

It is my object to avoid these disadvantages by providing unusually secure fastening means adapted to automatically open or close a storm sash upon the opening or closing of an inner, sliding sash.

A further object is to provide an automatic regulator of this kind, which is easy to attach and adapted to facilitate the removal and replacement of storm sash on windows. Other objects of my invention will appear and be more fully pointed out in the following specification and claims.

The invention will be best understood by reference to the accompanying drawings, in which Fig. 1 is a side elevation of my improved device mounted on a window, the window being shown in vertical section; Fig. 2 is a normally upper end view of the movement plate adapted to be attached to the storm sash; Fig. 3 is a plan view of the bracket, adapted to be connected to the inner sash, showing the movement plate in horizontal section; Fig. 4 is a side elevation of the bracket and fragmentary portion of the movement plate and Fig. 5 is a side elevation of an alternate form of movement plate and bracket.

As illustrated, my device is adapted to be

mounted upon a window having upper and lower sliding sashes 6 and 7 respectively. A removable storm sash 8 is pivoted upon hinges or hooks 9 at its upper end so as to swing outward from the window at its lower end. Upon each of two vertical, side members 10 of the sash 8, I mount a movement plate 11 having perforated flanges 12 adapted to be secured by screws to the members 10. A pair of guide flanges 13 project laterally from the inner edge of the plate 11 for engagement with rollers on a bracket 14. This bracket 14 is adapted to be secured to the inner sash 7, opposite the plate 11, and has a pair of branch portions 15, between which the plate 11 extends. A roller 16, journalled between the members 15, is adapted to run upon the inner faces of the flanges 13, and a pair of rollers 17 are arranged to extend into engagement with the outer faces of the flanges 13 respectively. As clearly shown in Fig. 1, the flanges 13 are so formed on the plate 11 that they extend substantially parallel to the flanges 12 for a short distance near the lower end of the plate and then diverge upward and finally extend substantially parallel to the flanges 12 near the upper end of the plate. Obviously, a bracket 14 may be attached to each vertical side member of the sash 7 to coact with a movement plate 11 placed opposite said bracket.

I prefer to so place the brackets 14 and plates 11 on the sashes that the brackets 14 will be out of engagement with the plates when the inner sash is in extreme upper or open position. Thus, when the storm sash is to be mounted on the window frame, the upper end of said sash is attached to the hooks 9, and with the lower sash in wide open position the storm sash is held in approximately the open position shown in Fig. 1 until the sash 7 is lowered to bring the rollers 17 on one side of the flanges 13 and the roller 16 on the opposite side of said flanges. Now, as the sash 7 is closed, the storm sash is moved to closed position by engagement of the rollers 17 with the outer faces of the flanges 13. When the inner sash 7 is in the closed or dotted line position, shown in Fig. 1, the rollers 17 remain in engagement with the flanges 13 to securely hold the storm sash in closed position.

An alternate form of my device is shown in Fig. 5. In this form, the roller 16 is eliminated and a second pair of flanges 18, simi-

lar to the flanges 13, are provided for engagement with the outer peripheries of the rollers 17. It will be evident that in this alternate form, the cost of the plate 11 is somewhat increased, but the bracket 14 is rendered less expensive, by reason of the elimination of the roller 16.

The operation of my device will now be evident. It is only necessary to open the inner sash 7 to effect the opening of the storm sash and the latter sash is closed automatically as the sash 7 is closed. By reason of the smooth, gradually curving form of cam surfaces on the flanges 13, an unusually easy and smooth running device is obtained. The operation of attaching the movement plate 11 and brackets 14 to the sashes is simple and may be accomplished quickly and easily.

Having described my invention what I claim as new and desire to protect by Letters Patent is:

1. The combination with a window having a sliding sash and a pivoted sash, of a movement plate, adapted to be secured to one of said sashes, a cam arranged on said plate to extend obliquely between said sashes, a bracket adapted to be secured to the other of said sashes, means on said bracket adapted to operatively engage said cam, an end of said cam formed to removably receive said engaging means when secured to said sashes, said plate and bracket being adapted to swing said pivoted sash to open position when said sliding sash is opened.

2. The combination with a window having an inner sliding sash and an outer pivoted sash, of a movement plate adapted to be secured to said outer sash, a bracket adapted to be secured to said inner sash, a flange on said plate, means on said bracket adapted to operatively engage said flange and to co-

act therewith in positively swinging said pivoted sash to open position when said sliding sash is opened and an end on said flange arranged to removably receive said engaging means while secured to said sashes.

3. The combination with a window having a vertically sliding sash and a storm sash pivoted at its upper end to swing outward at its lower end from said sliding sash, a movement plate rigidly secured to said storm sash and adapted to project inward therefrom adjacent to a vertical member of said sliding sash, a cam surface on said plate formed at its lower end to extend substantially parallel to said storm sash and having a contiguous portion diverging obliquely inward from said storm sash, and means on said sliding sash adapted to engage said cam surface and to coact therewith in imparting outward swinging movement to said storm sash when said inner sash is opened.

4. The combination with a window having a vertically sliding sash and a storm sash pivoted at its upper end to swing outward at its lower end from said sliding sash, a movement plate extending along and rigidly secured to a vertical member of said storm sash and adapted to project inward therefrom adjacent to said sliding sash, a laterally projecting flange on said plate, a cam surface formed to diverge obliquely inward from said storm sash, upper and lower end portions of said cam surface normally extending parallel to said sliding sash, and rollers on said sliding sash adapted to engage said cam surface and to coact therewith in imparting outward swinging movement to said storm sash when said inner sash is opened.

In testimony whereof, I have hereunto signed my name to this specification.

CHRISTIAN A. CHRISTOFFERSON.
